CLAIM

The ornamental design for a power end frame segment, as shown and described.

DESCRIPTION

FIG. 1 is a front perspective view of a power end frame segment;

FIG. 2 is a front view of the power end frame segment; FIG. 3 is a rear view of the power end frame segment; FIG. 4 is left side view of the power end frame segment, the right side view being a mirror image thereof;

FIG. 5 is a top view of the power end frame segment; and, FIG. 6 is a bottom view of the power end frame segment. The broken lines in FIGS. 1 through 6 form no part of the claimed design.

Although FIGS. A-F form no part of the claimed design, FIGS. A through F depict a power end frame segment that includes the claimed design. FIG. A is a front perspective view of the power end frame segment. FIG. B is a front view of the power end frame segment. FIG. C is a rear view of the power end frame segment. FIG. D is a left side view of the power end frame segment, the right side view being a mirror image thereof. FIG. E is a top view of the power end frame segment. FIG. F is a bottom view of the power end frame segment.

1 Claim, 4 Drawing Sheets
